UNITED STATES PATENT OFFICE.

WILLIAM RUBIN, OF SOUTH OMAHA, NEBRASKA.

ROUND-CAN-FLOATING MACHINE.

SPECIFICATION forming part of Letters Patent No. 743,567, dated November 10, 1903.

Application filed January 30, 1902, Serial No. 91,930. (No model.)

To all whom it may concern:

Be it known that I, WILLIAM RUBIN, a citizen of the United States, residing at South Omaha, in the county of Douglas and State of Nebraska, have invented certain new and useful Improvements in Round-Can-Floating Machines; and I do hereby declare the following to be a full, clear, and exact description of the invention, such as will enable others skilled in the art to which it appertains to make and use the same.

The object of my invention is to provide a simple, inexpensive, and efficient mechanism for soldering the heads and bottoms of tin or sheet-metal cans to the bodies thereof.

It is a further object of my invention to provide means for adjusting the said mechanism to admit of using the same machine for soldering or "floating," as it is usually called, several sizes of cans.

With these objects in view the invention consists in the improved construction, arrangement, and combination of parts herein-after fully described and afterward specifically claimed.

The general construction of a machine embodying my invention is shown in the accompanying drawings, in which—

Figure 1 is a side elevation partly in section. Fig. 2 is a sectional elevation on the line X X of Fig. 1. Fig. 3 is a perspective view of the turn-over device at the end of the upper can-track. Fig. 4 is a detail end view of part of the solder-feeding mechanism. Fig. 5 is a side view of the same, and Fig. 6 is a sectional view of the lower solder-pot and the adjustable support for the sheaves for the can-rotating cable. Fig. 7 represents an enlarged perspective view of the solder-pots and can-positioning guide with surrounding parts broken away.

In the construction of the machine I employ a number of pairs of suitable standards 1 1^a 1^b 1^c, one of each pair on each side of the machine, which standards at their lower ends are secured upon suitable base-blocks 2 and at their upper ends are held together by brackets 3. Between the brackets 3 are sections of pipe 4, through which passes a rod 5, having nuts 6 on the ends thereof, which when

tightened hold the sections of pipe in position and keep the standards properly spaced.

Between the end pair of standards 1 and 1^c are journaled in suitable bearings the shafts 7 and 8, carrying the sprocket-wheels 9 and 10. 55

The bearing-boxes for shaft 8 are placed in slotted openings 11 in standards 1 and have adjusting-screws 12 for tightening an endless chain 13, which passes around the sprockets 9 and 10. 60

The chain 13 is provided at regular intervals with flat fingers 14, as shown in Figs. 1 and 2 and best shown in Fig. 3, secured on edge and projecting laterally beyond the side of the chain. 65

Except while passing around the sprockets 9 and 10 the chain 13 rests on a track formed of longitudinal angle-irons 15 15, which are supported by transverse angle-irons 16 16, secured to the pairs of standards 1 1^a 1^b 1^c. 70

Adjacent to the sprocket-wheel 10 is an inclined chute 17, in which the cans A to be soldered are placed. At the lower end of this chute the cans are caught by the projecting fingers 14 on the chain and carried upward 75 around the curved track 18. After passing between the first pair of standards 1 this track is slightly inclined laterally, so that the cans are tipped over to bring the edge of the bottom downward and in this position 80 are rolled through the solder-pot 19. This pot is supported alongside of and below the chain-tracks 15 by the longitudinal bars 20, secured to the standards 1 1^a, and by transverse bars 21. While rolling through 85 the solder-pot the cans are held down into the solder and given an additional rolling movement by a continuous cable 22, which is held in position against the cans by small idler-sheaves 23, which are adjustably secured to standards 24, projecting upwardly from the bars 20. In suitable bearings on the standards 1 1^a are the shafts 25 and 26, carrying sheaves 27 and 28 for cable 22. The shaft 26 is driven through the medium of a 95 pulley 29 thereon and a belt 30, connecting said pulley with a second pulley 31 on a shaft 32, carrying a sprocket 33, connected by a chain 34, extending around a sprocket 35 on the shaft 7. 100

On shaft 25 an arm 36 is pivoted, which carries on its opposite end a small idler-sheave 37, which rests on the cable 22, keeping the same taut.

5 The cans after rolling through the pot 19 pass over a guide 38, which is inclined laterally and further turns the can so that it rests on its bottom. In this position the cans are slid along a track one side of which is 10 formed of one of the angle-irons 15 of the chain track and the other side of which consists of an angle-iron 39, as shown in Figs. 1 and 3. The bottom of this can-track is formed of bars 40 and 41 of rounded strap-iron, which 15 are secured to and supported by cross-pieces 42, which in turn are secured to the chain-track irons 15 and the side piece 39. The cross-pieces 42 have a number of holes 43 therein, so that the side bar 39 and bar 41 20 may be set in varying positions thereon in order to widen the track to accommodate various sizes of cans.

At the end of the upper can-track, which is shown in Fig. 3, one of the bars 40 extends 25 beyond the end of the other bar 41 and is slightly curved upward. When the cans are pushed off this track by the fingers 14 of the chain, they are supported and raised on one side by this bar 40, so that they are further 30 turned a full quarter-way round and drop over on their sides into the flaring end of the chute 44 and roll down the same, following the line of travel of the chain 13 around the sprocket 9. At the lower end of this chute 35 44 the cans are further slightly turned to cause the edges of their tops to roll through a second solder-pot 45, as shown in Figs. 2 and 6, the said tops being open heads of well-known form. While passing through this 40 pot the cans are rolled faster and held in position as before by a cable 22^a, passing around adjustable idlers 23^a, mounted in standards 24^a, sheaves 27^a and 28^a, and tightening-idler 37^a of substantially the same construction 45 and arrangement as the corresponding parts hereinbefore described, the cable 22^a passing around sheaves on shafts 32 and 32^a, as shown in Fig. 1. After passing the pot 45 the cans are further turned on their top ends by the 50 inclined sides of a laterally-inclined guide 38^a and in this position slide along a track as before until reaching the sprocket 10, where the track ends and the cans are dumped upon a conveyer or into suitable receptacles. 55 It will be observed that the upper and lower solder-pots and guides are exact duplicates of each other, and I have illustrated the upper one in perspective, so that the construction of both may be fully comprehended. 60 The lower track from the solder-pot 45 to the end of said track is covered, as shown in Fig. 1, by an elongated box 66, which has openings 67 in its ends large enough to admit of the passage of the cans and driving chain and to permit of the insertion in said box of the tracks therefor. Inside the box 65

66 and below the can-track is a pipe 68, which has on its upper side a number of small nipples or jets 69, which extend up close to the track. While the cans are passing along the 70 track steam or water under pressure from any suitable source is forced into the pipe 68 and through the jets 69. As the open ends or heads of the cans are downward, this steam or water will enter the cans, and also on the 75 steam or water striking the top of the box between the cans 66 it will drop down on top of the cans, so that the cans will be washed thoroughly inside and out in passing through the box 66. A drain-pipe 70 at one end of 80 the said box serves to carry off the water or steam.

The construction of the solder-pots 19 and 45 is substantially similar, and the latter is shown in Fig. 6, which illustration will serve 85 for the pot 19 also. It will be seen that the pot has a hollow space 46 below for the introduction of a suitable heating medium for keeping the solder melted. Above this space is the pot proper for containing the solder, 90 comprising a space 47, which extends into a projection 48 on the rear side of the pot. This space 47 is provided with a cover 49, on which the cans rest and which has a projecting rib 50 for holding the cans down, so that 95 their edges will be sure to dip into the melted solder. Solder in the form of ribbon or wire is supplied to the pot 47 through a pipe 51, as follows, as best shown in Fig. 2: On a shaft 32 is an eccentric 52, which is connected by 10. a twisted bar 53 to a link 54, which is adjustably secured to the pawl-arm 55 on shaft 56. This shaft extends longitudinally of the machine and is supported in suitable bearings carried by the standards 1 and 1^a. Adjacent to the pawl-arm 55 on shaft 56 is a ratchet 57, with which a pawl 57^a, pivoted to the arm 55, engages, so that the movement of the said eccentric will cause an intermittent rotation of the said shaft, the extent of which 110 will be controlled by the adjustment of link 54 on pawl-arm 55.

Centrally above the solder-pots 19 and 45 on the shaft 56 are wheels or disks 58 58^a, having in their peripheral surface grooves or 115 depressions 59. (See Figs. 4 and 5.) Within these grooves run smaller disks 60 60^a on arms 61 61^a, which are pivoted on the sections of the pipe 4 between the standards. Springs 62 62^a are attached to the arms and to loose 120 collars 63 63^a on the shaft 56 and hold the disks 60 60^a yieldingly in contact with the disks 58 58^a. A wire or ribbon of solder 51^a is introduced between these disks 58^a and 60^a, Figs. 1 and 2, and passes down the pipe 125 51^a to the solder-pot 45, being intermittently fed by the action of the ratchet and eccentric mechanism, as described.

Pipe 51^a serves to conduct solder-wire 51 to solder-pot 19, the wire being actuated by the 130 disk 58 on shaft 56, disk 60, mounted on arm 61, pivoted to pipe 4, and spring 62, connect-

ing the arm to a loose collar 63 on shaft 56, these parts being similar in construction and arrangement to the corresponding parts used in connection with solder-pot 45, as before described.

- The operation of the machine is as follows: Wires or ribbons of solder are passed between the feed-disks, and the position of the links 54 on the pawl-arms is adjusted to give the proper amount of feed to the ratchets and the disks. The heating apparatus is started under the solder-pots until the solder is melted and fills the spaces 47 of the pots to a sufficient depth. Power is applied to the pulley 65 on shaft 7, and the various chains, belts, sprockets, sheaves, cables, &c., are driven, as described. The cans to be soldered are placed in the feed-chute and roll down the same until they reach the track 18, when they are engaged by the fingers 14 on the chain 13 and carried upward and rolled through the solder-pot 19, so that one edge of the bottom of the can dips into the solder contained therein. This rolling is assisted by the cable 22, which, it will be observed, travels in the same direction as the cans and at greater speed. On passing over the pan 38 the inclined sides of the same turn the cans over, so that they rest on their bottom ends and in this position are slid along the upper track until they reach the end thereof, when they drop into the chute 44 and roll down the same. In dropping into this chute the cans are further turned a quarter-way round, so that the edges of the top of the can which have not been soldered are toward the front side of the machine. In this position they are rolled through the pot 45 and this remaining or top edge is soldered. On passing the guide 38^a the cans are further turned a quarter-way round, so that they rest on their heads or open ends and in this position are slid along the lower track and through box 66, being washed inside and out while therein, as described.

By means of the described construction I am enabled to solder both heads of the can and to thoroughly wash it inside and out without the necessity of handling the can during any part of both operations, and while I have specifically described the construction and operation of the various parts I desire it to be understood that I do not confine myself to the exact constructions and arrangement, but hold that many minor changes and variations therein might be made without departing from the spirit and scope of my invention.

Having now described my invention, what I claim as new, and desire to secure by Letters Patent, is—

1. In a can-soldering machine the combi-

nation with a traveling endless chain designed to convey cans, and a solder-pot through which said chain moves, of an endless cable suitably mounted to bear upon a can while 65 being moved through the solder-pot by said chain, and means for moving said cable in the direction of the traveling chain faster than the normal travel of the chain, substantially as described.

2. In a can-soldering machine, the combination with a traveling endless carrier and a solder-pot over which said carrier moves, of an endless cable traveling in the direction of the travel of said carrier and at a greater 75 speed than the same, and suitably mounted to bear upon a can carried over said solder-pot on said carrier for rotating the can during its movement through the solder-pot, substantially as described.

3. In a can-soldering mechanism, the combination with a can-support inclined laterally, a solder-pot provided with a groove having an inclined side at an angle to the inclined can-support, supporting-shafts, pulleys carried thereby, adjustably-journalized idler-sheaves, a cable passed upon said pulleys and sheaves and bearing upon the side of the can and rotating the same through the solder-pot, and independent can-moving 90 means for directing the same along the can-support in the direction of movement of said cable and at a less rate than the movement of the cable, substantially as described.

4. In a can-soldering machine, the combination with a traveling endless chain and a solder-pot over which said chain moves, of an endless cable traveling in the direction of travel of the said chain and suitably mounted to bear upon a can carried over the solder-pot by the chain, whereby the can is rotated in the solder, substantially as described.

5. In a can-soldering machine, the combination with a can-support inclined laterally, a solder-pot provided with a groove having an 105 inclined side at an angle to the inclined can-support, can-moving means arranged for conveying a can along the can-support and into and through the solder-pot, a cable moving in contact with said can in the direction of 110 movement of said can-moving means, and means for moving said cable at a higher rate of speed than the travel of the can-moving means whereby the can is revolved while the seam thereof is in contact with the molten 115 solder, substantially as described.

In testimony whereof I hereunto affix my signature in presence of two witnesses.

WILLIAM RUBIN.
